(57) **CLAIM**

We claim the ornamental design for a computing device jacket, as shown and described.

DESCRIPTION

FIG. 1 is a front perspective view of a computing device jacket receiving a computing device;

FIG. 2 is a front perspective view of the computing device jacket with the computing device removed;

FIG. 3 is a rear perspective view of the computing device jacket;

FIG. 4 is a front view thereof;

FIG. 5 is a rear view thereof;

FIG. 6 is a top view thereof;

FIG. 7 is a bottom view thereof;

FIG. 8 is a right side view thereof;

FIG. 9 is a left side view thereof;

FIG. 10 is a rear perspective view of the computing device jacket with a rear access panel removed; and,

FIG. 11 is a rear perspective view of the computing device jacket containing a computing device and with a cap portion partially removed.

The broken lines in the drawings are for illustrative purposes only and form no part of the claimed design.
